ANHYDROUS HERBICIDAL CONCENTRATE
Frederick J. Wolter, West Chester, Pa., assignor to E. I.
du Pont de Nemours and Company, Wilmington, Del.,
a corporation of Delaware
No Drawing. Filed Nov. 30, 1962, Ser. No. 241,177
1 Claim. (Cl. 71—2.6)

This application is a continuation-in-part of copending application Serial No. 94,426, filed March 9, 1961; applications Serial No. 735,362, filed May 15, 1958, and Serial No. 550,749, filed December 2, 1955 all abandoned; and Serial No. 313,044, filed October 3, 1952, and issued as U.S. Patent No. 2,726,150.

This invention relates to herbicide concentrates and is more particularly directed to stable herbicide concentrates comprising herbicide particles dispersed in nonsolvent oils.

Concentrates of herbicides in oils have been known for many years. The herbicides in these concentrates have an unfortunate tendency to settle into dense deposits, and their crystal size frequently grows because of fluctuating storage temperatures. Such compositions can then be resuspended and diluted only with difficulty and are inconvenient to spray because the large particles clog nozzles.

A superior oil concentrate having none of these disadvantages can be prepared according to this invention by suspending the active herbicide in a nonsolvent oil, adding lecithin, and then milling the composition until the particle diameter has been reduced to below 5 microns.

The herbicides which can be formulated in this fashion are the substituted ureas and the substituted triazines. The herbicidal ureas which are especially suited for formulation are those of the formula

where

X is halogen,

n is 1, 2, or 3,

R1 is methyl or ethyl, and

R2 is hydrogen, alkyl of one through four carbon atoms, or alkenyl of one through four carbon atoms.

Illustrative of these ureas are:

- 3-(p-chlorophenyl)-1,1-dimethylurea
- 3-(3,4-dichlorophenyl)-1,1-dimethylurea
- 3-(3,4-dibromophenyl)-1,1-dimethylurea
- 3-(3,4-dichlorophenyl)-1-methylurea
- 3-(p-chlorophenyl)-1-methylurea
- 3-(p-chlorophenyl)-1-methyl-1-isopropylurea
- 3-(p-chlorophenyl)-1-methyl-1-allylurea
- 3-(m-chlorophenyl)-1,1-dimethylurea
- 3-(3,4-dichlorophenyl)-1,1-diethylurea
- 3-(3,4-dichlorophenyl)-1-methyl-1-isopropylurea
- 3-(3,4-dichlorophenyl)-1-methyl-1-butylurea
- 3-(3,4-dichlorophenyl)-1-methyl-1-sec.butylurea
- 3-(p-chlorophenyl)-1-methyl-1-ethylurea
- 3-(p-bromophenyl)-1,1-dimethylurea
- 3-(p-fluorophenyl)-1,1-dimethylurea
- 3-(p-chlorophenyl)-1-methyl-1-n-propylurea
- 3-(p-chlorophenyl)-1-methyl-1-sec.butylurea
- 3-(p-iodophenyl)-1,1-dimethylurea
- 3-(3,4-dichlorophenyl)-1-methyl-1-ethylurea
- 3-(3-bromo-4-chlorophenyl)-1,1-dimethylurea
- 3-(2,4,5-trichlorophenyl)-1-methylurea
- 3-(p-bromophenyl)-1-methyl-1-isopropylurea
- 3-(p-chlorophenyl)-1,1-diethylurea
- 3-(2,4,5-trichlorophenyl)-1,1-dimethylurea
- 3-(m-chlorophenyl)-1-methylurea
- 3-(p-bromophenyl)-1-methylurea
- 3-(p-chlorophenyl)-1-ethylurea
- 3-(m-chlorophenyl)-1-methyl-1-isopropylurea

2

Herbicidal triazines which can be formulated according to this invention are those of the formula

where

10 X is chloro, methoxy, or methylmercapto, and R1 and R2 are alkyl of less than 4 carbons, or a —(CH2)n—OCH3 radical, where n is 2 or 3.

Illustrative of these triazines are:

- 15 2,4-bis(ethylamino)-6-methylmercapto-1,3,5-triazine
- 2,4-bis(ethylamino)-6-chloro-1,3,5-triazine
- 2,4-bis(isopropylamino)-6-chloro-1,3,5-triazine
- 2-chloro-4-ethylamino-6-isopropylamino-1,3,5-triazine
- 2-ethylamino-4-isopropylamino-6-methoxy-1,3,5-triazine
- 20 2-chloro-4-ethylamino-6-(3-methoxypropylamino)-1,3,5-triazine

The precise amount of active ingredient to be used in the concentrates of this invention of course depends on the ultimate use of the composition and is governed by such factors as the type of plant to be treated, climatic factors, the degree of control desired, and the like. Generally, however, the concentrates are formulated to contain from 10% to 60% of active ingredient.

30 It is essential that the oil used dissolve no more than 0.1% by weight of the active ingredient at 30° C. Oils dissolving more active ingredient than this promote the growth of large crystals on storage. For the same reason, it is desirable that the oil have a sulfonatable residue of no more than 20%, and be anhydrous.

Preferred oils are the petroleum hydrocarbon fractions obtained from paraffin-base petroleum, such as diesel oil, lubricating oils, and mineral oils. These oils have viscosities of from 25 to 10,000 Saybolt Universal seconds at 100° F. and boiling points of from 200 to 680° F. Oils with viscosities of from 25 to 400 Saybolt Universal seconds are especially preferred.

Preferred concentrates contain 1-5% lecithin, 3% being the optimum. Lecithin aids in dispersing the ingredients without promoting excessive crystal growth and retards the formation of solid cakes in containers on storage, which make resuspension difficult. Lecithin also improves dispersion of the active ingredients when the concentrates are diluted to use levels in oils.

50 It is essential that the use of water and emulsifying agents other than lecithin be avoided in formulating the concentrates. Other emulsifying agents cause the formation of large crystals on long-term storage, and the presence of water tends to promote flocculation and makes the concentrates corrosive to metals and incompatible with other herbicidal oil formulations. The concentrates are therefore preferably anhydrous.

55 It is also essential that the solid ingredients of these concentrates have an average particle diameter of less than 5 microns. The concentrates are accordingly prepared by mixing the herbicide with the anhydrous oil and then grinding or milling the mixture in an ink or paint mill.

60 Alternatively, the dry ingredients can be ground separately in jet-impact or ball mills and then added to the oil.

A highly preferred method, however, is to mix the herbicide with an oil and lecithin and then grind this mixture in a sand mill. A suitable apparatus and directions 70 for its use are disclosed in Hochberg U.S. Patent No. 2,581,414.

Such an apparatus can grind the concentrates to the

desired particle size in from 15 to 45 minutes or more, depending on the initial particle size of the solids. The optimum time is best determined by inspection.

The oil formulations prepared according to these methods are highly stable and resist caking in storage. Prior to application, they can be extended with herbicidal oils or other carriers to give sprayable compositions which are also stable and resist settling. These diluted compositions are best used according to the methods prescribed for the active ingredient.

This invention will be more easily practiced by referring to the following illustrative examples:

Example 1

A mixture of 60 parts of crystalline 3-(p-chlorophenyl)-1,1-dimethylurea and 40 parts of lubricating oil is prepared. The oil is a Mid-Continent, solvent-treated petroleum oil, predominantly paraffinic, with a viscosity of 300 Saybolt Universal seconds at 100° F., and dissolves less than 0.1% of the urea at 30° C.

This mixture is milled by six successive passes through a Kent 3-roll ink mill with 4-inch rolls set at 0.001 to 0.0015 inch clearance. The substituted urea is uniformly dispersed as particles of less than 5 microns average diameter, with most of the particles being 1 micron or less. This dispersion is in the form of a thick putty-like paste.

Equal parts of this paste and the lubricating oil are then mixed to give a pourable fluid composition containing 30% substituted urea. This concentrate has excellent shelf life and does not form a hard cake in the container upon storage.

Example 2

A mixture of 30 parts of 3-(3,4-dichlorophenyl)-1,1-dimethylurea, 5 parts soya lecithin, and 69.5 parts of light mineral oil is mixed with an equal volume of 20-30 mesh Ottawa sand. The oil has a viscosity of 35 S.U.S., a sulfonatable residue of 15%, and dissolves less than 0.1% of the urea at 30°.

This mixture is agitated for 30 minutes at 2700 r.p.m. in a sand mill of the kind described in U.S. Patent 2,581,414.

The resulting concentrate, after separation from the sand by centrifuging, is a thixotropic composition which does not settle, even after extended storage periods. Substantially all of the substituted urea particles are less than 5 microns in diameter.

Example 3

A slurry of 25%, 2,4-bis(ethylamino)-6-chloro-1,3,5-triazine in 75% "Sovaspray Oil No. 2" is prepared.

"Sovaspray Oil No. 2" is a dormant spray oil sold by the Socony Mobil Oil Company; it has a viscosity of 100-105 S.U.S. at 100° F., a sulfonatable residue of 8%, and dissolves less than 0.1% of the triazine at 30° C.

The slurry is pumped to a continuous sand mill. The total residence time in the mill is about 20 minutes. The product contains particles of active material which are under 5 microns in diameter. The stable suspension so formed can then be diluted with a herbicidal oil and sprayed.

Example 4

Percent

2-chloro-4-isopropylamino-6-ethylamino-1,3,5-triazine	30

15 Soya lecithin	1

"Liteteck" mineral oil	69

("Liteteck" mineral oil is a highly refined white oil sold by the Pennsylvania Refining Company. It has a viscosity of 50-60 S.U.S. at 100° F., and dissolves less than 0.1% of the triazine at 30° C.)

These components are mixed and milled in the same manner as described in Example 3.

Example 5

Parts

25 3-(p-chlorophenyl)-1,1-dimethylurea	30

Soya lecithin	3

Light mineral oil (viscosity 60 S.U.S.)	67

The oil is heated to remove all traces of water. The other ingredients are then added and the mixture is sand milled as described in Example 3.

The embodiments of the invention in which an exclusive property or privilege is claimed are:

An anhydrous herbicidal concentrate comprising 30 parts of 3-(p-chlorophenyl)-1,1-dimethylurea, 3 parts of lecithin and 67 parts of mineral oil, said urea having an average particle diameter of less than 5 microns.
